UNITED STATES PATENT OFFICE

150,161

DESIGN FOR A MOTOR CAR

Roger Laurent Jean Baptiste Sanmori,
Monaco, Monaco

Application June 1, 1946, Serial No. 130,312
In France March 12, 1946

Term of patent 14 years

(Cl. D14—3)

To all whom it may concern:

Be it known that I, Roger Laurent Jean Baptiste Sanmori, subject of the Prince of Monaco, residing at Monaco (Principality of Monaco) 2 impasse des Carrières, have invented a new, original, and ornamental Design for Motor Car, of which the following is a specification, reference being had to the accompanying drawings, forming part thereof.

Fig. 1 is a front three-quarter perspective view of a motor car, showing my new design, with one door opened;

Fig. 2 is a side perspective view of the same motor car, with both doors closed;

Fig. 3 is a top plan view with both doors closed.
I claim:

The ornamental design for a motor car, as shown.

ROGER LAURENT JEAN
BAPTISTE SANMORI.
